UNITED STATES PATENT OFFICE.

LOUIS PROPP, OF NEW YORK, N. Y.

PLUG SOCKET.

Application filed July 23, 1921. Serial No. 487,204.

This invention relates to electrical plug sockets.

More particularly, this invention relates to plug sockets adapted for use with Christmas tree outfits or display window lighting, or the like decorative electric devices, employing festoons of electric lamps or other such appliances. One object thereof is to provide a device of this character whereby one or 10 more festoons of lamps may be independently connected to the electric supply.

Another object is to provide in combination with a plug socket of the character described, a unit or festoon adapted to be connected thereto of such construction as to permit any number of such units to be independently connected to the source of electric supply.

A further object is to provide a practical 20 device of the character described which shall be simple and compact in construction and cheap to manufacture.

Other objects of this invention will in part be obvious and in part hereinafter pointed 25 out.

The invention accordingly consists in the features of construction, combinations of elements and arrangement of parts which will be exemplified in the construction hereinafter described and of which the scope of invention will be indicated in the following 30 claims.

In the accompanying drawing, in which is shown one of various possible illustrative 35 embodiments of this invention,

Fig. 1 is a plan view of a plug socket embodying this invention showing the same in use with several units or festoons of lamps connected thereto;

40 Fig. 2 is an end view of the socket;

Fig. 3 is an end cross-sectional view taken along line 3—3 of Fig. 1 of the socket with a connecting plug in place thereon;

Fig. 4 is a plan view of the plug socket 45 with one-half of the two part casing removed to show the interior;

Fig. 5 is a perspective view showing one-half of the two-part casing of the socket; and

50 Fig. 6 is a perspective view of the metal conducting bar of the plug socket.

Referring in detail to the drawing, the plug socket embodying the invention there shown comprises a casing 10 of insulating

55 material consisting of halves 11 and 12 adapted to be secured together by means

such as a counter-sunk screw 13. Each of the halves is formed on the interior thereof with a pair of longitudinal channels 14 preferably of the shape shown in Fig. 5 and which are arranged in each half symmetrically with respect to a medial dividing wall 15. Enclosed within the casing is a pair of connectors 16 preferably of brass and of the shape as shown in Fig. 6, so as to fit 60 snugly into the channels 14 when the two halves are put together. At one end of each connector is a binding post or connecting screw 17 to which are attached the lead wires from the mains as shown at 18 in Fig. 1.

The walls of the channels 14 are indented at spaced intervals as at 14^a and the medial wall 15 of the casing correspondingly indented as at 14^b so as to form between each 75 pair of the indented walls 14^a and 14^b a socket 19 for the reception of one of the connecting members 20 of the plug 21. It will be understood of course that the indented walls 14^a and 14^b extend the complete depth of the half of the casing, thus providing on the front and rear thereof a plurality of openings 22. The current may thus be tapped from a connector 16 by inserting a plug 21 into any of the openings 80 22, each connecting member 20 entering into its corresponding recess 19 and frictionally engaging these plugs so as to give good electrical contact. Any number of openings 22 of the character hereinbefore described may 85 be provided, thus making it possible to connect one or more of these plugs simultaneously to the socket for the purpose of supplying one or more independent circuits. In the embodiment of the invention shown in the 90 drawing, the plug socket is applied to supplying festoons from miniature lamps 23 connected in series with the lead wires 24, 25 issuing from the plug socket.

The unit or festoons of lamps provided in 100 connection with the attachment plug will now be described. This comprises a plurality of miniature lamps 23 connected in series by the leads 24 and 25 issuing from the lamp cord 26.

The free end of the unit is provided with a plug 21 having extending therefrom a pair of contact members 20 whereby the connection is made to the mains as already described.

110 It will be readily understood that any number of units may be used as desired by

2
plugging in each pair of the openings 22 on both sides and ends of the casing as shown in Fig. 1. Instead of keeping in stock fes-
toons of lamps of different arrangement,
such for example as eight in series, or a fes-
toon having two rows of eight in series, each
connected in parallel or three or four such
multiple rows, a dealer may keep in stock
units such as just described and separate
10 units will be sold where a single unit of
several rows of lamps arranged in multiple
lines would have been necessary. Thus, a
dealer does not have to run the risk of being
over-stocked in the various kinds of mul-
tiple units. Furthermore, in the practical
15 use such as in lighting a Christmas tree with
units herein provided, there is the advantage
that if anything goes wrong with the cir-
cuit, the bad unit may be disconnected very
readily without affecting the rest of the
20 lights of the tree. This is not possible
where multiple units are used. Electrical
trouble is furthermore more readily located
where the single units and attachment plug
provided by this invention are employed.

It will thus be seen that there is provided
a device in which the several objects of this
invention are achieved and which is well
adapted to meet the conditions of practical
use.

As various possible embodiments might be
made of the above invention and as various
changes might be made in the embodiment
above set forth, it is to be understood that
35 all matter herein set forth or shown in the
accompanying drawings is to be interpreted
as illustrative and not in a limiting sense.

Having thus described my invention, I
claim as new and desire to secure by Let-
ters Patent:—

1. In an electric plug socket, an insulating
casing formed of two halves, said halves be-
ing recessed on their interiors to form, when
secured together, a pair of longitudinal
45 channels, the casing having opposed open-
ings communicating with the channels from
the outer faces thereof, a pair of flattened
conductor bars within said channels, extend-
ing laterally equal distances beyond the di-
50 viding line of the casing halves, the casing

and bars being of such a width as to permit
simultaneous insertion of plugs in each of
said openings.

2. In a unit for connecting a series of
electrical appliances, an insulating casing 55
formed of two halves, said halves being re-
cessed interiorly to form, when secured to-
gether, a pair of longitudinal channels, the
casing having opposed openings communi-
cating with the channels from the outer 60
faces thereof and openings communicating
with the channels at the ends of the casing,
conductor bars within said channels of such
a width as to permit simultaneous insertion
of plugs in each of said openings. 65

3. A multiple plug socket connector com-
prising a two-part casing of insulating ma-
terial having spaced recesses extending lon-
gitudinally thereof to provide channels sep-
arated by a partition of insulating material, 70
the walls of the channels being cut away at
spaced intervals so as to provide opposed
socket openings communicating with the ex-
terior of the casing and adapted to receive
simultaneously plug members in each of said 75
openings, and electrical conductors located
in said channels and accessible through said
openings for electrical connection with said
plug members with the exterior surface of
said conductors. 80

4. A multiple plug socket, a connector
comprising a two-part casing of insulating
material, said parts being similar, each hav-
ing spaced recesses extending longitudinally
thereof so as to provide channels separated 85
by a partition of insulating material, the
walls of the channels and the end walls of
the casing being cut away to form opposed
socket openings extending through the sides
and ends of the casing to provide spaced 90
sockets at the sides and ends of the casing,
and electrical conductors located in said
channels, the casing and bars being of such
a width as to permit simultaneous insertion
of plugs in each of said sockets. 95

Signed at New York city, in the county of
New York and State of New York, this 21st
day of July, 1921.

LOUIS PROPP.
